UNITED STATES PATENT OFFICE

WALTER E. LILIENFIELD, OF CHICAGO, ILLINOIS, ASSIGNOR TO LILIENFIELD BROS. & COMPANY, OF CHICAGO, ILLINOIS

METHOD OF CURING TOBACCO

REISSUED

No Drawing.

Application filed March 17, 1927. Serial No. 176,303.

The invention relates to a method of curing tobacco. In the manufacture of tobacco for smoking, it is necessary before blending and mixing to 5 cure the strong and harsh raw material so as to modify its disagreeable taste and make it mild. It is now common practice to cure it by ageing the material or by artificially obtaining the same result by a renewed fermentation induced by moisture and heat, or macerating the leaves in water acidulated with hydrochloric acid or some other chemical, and washing them out with pure water. These curing methods are objectionable be- 10 cause they require a great deal of labor and time and are not as effective as desired in rendering the strong tobacco mild.

The object of the present invention is to provide a new and improved method of curing strong and harsh tobacco preparatory to mixing and blending, which requires less time and labor than former methods, and effectively renders the strong tobacco mild and fine so that it has an aromatic and pleasant flavor.

25 The improved method of curing is applied to the tobacco after it has been aged and fermented and consists in loosening and piling the tobacco leaves and then subjecting them to an ultra-violet ray. The latter may be 30 produced by any suitable apparatus which is positioned above the pile a sufficient distance so that the leaves are not affected by the heat generated by the ray. The ray is applied from 15 minutes to 2 hours depending upon 35 the quality and thickness of the tobacco under treatment and the mildness desired.

In practice, this method of curing has been found to eliminate the necessity of ageing the tobacco for a long time or the labor involved 40 in curing it by other methods. It has also been found to be the only method whereby any desired mildness may be obtained.

Having thus described the invention, what I claim as new and desire to secure by Letters 45 Patent, is:

That improvement in rendering mild and curing strong tobacco which consists in loosening previously aged and fermented tobacco leaves and then subjecting them to a machine 50 created ultra-violet ray for a period ranging

approximately from fifteen minutes to two hours to render them of the desired mildness.

Signed at Chicago, Illinois, this 15th day of March, 1927.

WALTER E. LILIENFIELD.
